UNITED STATES PATENT OFFICE.

CHARLES KOZESNIK, OF NEW YORK, N. Y.

THIRD-RAIL ELECTRIC-RAILWAY SYSTEM.

No. 870,564.

Specification of Letters Patent.

Patented Nov. 12, 1907.

Application filed June 16, 1904. Serial No. 212,770.

To all whom it may concern:

Be it known that I, CHARLES KOZESNIK, a citizen of the United States, and residing at New York, in the county of New York and State of New York, have invented certain new and useful Improvements in Third-Rail Electric-Railway Systems, of which the following is a specification, such as will enable those skilled in the art to which it appertains to make and use the same.

This invention relates to third rail electric railway systems, and particularly to elevated railways of the class, and the object thereof is to provide a railway system of this class in which the third rail or conductor in connection with which the contact shoes of the cars or motors operate, is composed of separate sections, which are in circuit only when the contact shoes of the cars or motors are bearing thereon; and with this and other objects in view the invention consists in a third rail electric railway system constructed as hereinafter described and claimed.

20 The invention is fully disclosed in the following specification, of which the accompanying drawing forms a part, in which the separate parts of my improvement are designated by suitable reference characters in each of the views, and in which:—

25 Figure 1 is a sectional side view of separate sections of the third rail of an electric railway system and showing one of the car or motor shoes in connection with one of said sections, together with the circuit forming and closing devices used in connection with said sections;

30 Fig. 2 a section on the line 4—4 of Fig. 1 and on an enlarged scale.

In the drawing forming part of this specification, reference being made to Fig. 1, I have shown at *a* the sleepers or supports of the third rail *b*; and said third rail is composed of separate sections *b*², and on said sleepers or supports are secured box-shaped holders *c* which correspond with the separate sections *b*² of the third rail, and the said separate sections of the third rail and said box-shaped holders *c* extend the full

40 length of the track, the rails of which are not shown. The box-shaped holders *c* are open at the top, and the separate sections *b*² of the third rail are provided with depending and laterally directed side flanges *b*³ which are bolted to corresponding side flanges *c*² on the sides

45 *c*² of the box-shaped holder *c*, and between the flanges *b*³ and *c*² are placed insulating material *d* as clearly shown in Fig. 2. At regular intervals within the box-shaped holders *c* are placed armature supports *e* which rest on the bottom of the box-shaped holders *c* and are

50 insulated therefrom as shown at *d*², and two of which are employed in connection with each of the third rail sections *b*. Each of the armature supports *e* consists of two pairs of uprights *e*² connected with a base plate *e*² insulated from the bottom of the box-shaped holder *c*,

55 and the separate pairs of uprights *e*² range transversely of and beneath the third rail and are provided in their

upper ends with notches or recesses *e*⁴ in which are placed armatures *e*⁵ which range longitudinally of the third rail sections and are vertically movable, and are provided with guide pins *e*⁶ movable in the notches or recesses *e*⁴, and each of the armatures *e*⁵ is provided with contact points or devices of copper *e*⁷ which are secured thereto, and over each of the contact devices *e*⁷ and secured to the bottom of the third rail *b* is a copper plate *e*⁸. The contact devices *e*⁷ beneath each section *b*² of the third rail are connected by a wire *f*, and running parallel with the track and incased and supported in any desired manner is a main supply wire *f*² which is connected with the wires *f* by feed wires *f*³, preferably provided with switches *f*⁴. The contact shoes *g* which operate in connection with the said third rail are each provided with a magnet *h* that after starting is energized by the current from the rail and as the car or motor moves along the track and the shoes *g* come in contact with the separate third rail sections *b*², the armature *e*⁵ beneath said third rail sections are picked up and assume the position shown at the left of Fig. 1, and the circuit is completed from the main wire or conductor *f*² through the contact devices *e*⁷, the separate sections of the third rail, the contact shoes *g* and the proper connections to the motor, which is not shown. It will thus be seen that the separate third rail sections *b*² are never in circuit except when the contact shoes *g* are resting thereon, and said third rail sections are thus made entirely harmless and no injury is occasioned by coming in contact therewith.

It will be understood that the means herein described may be applied to third rail electric railway systems of any kind or class and to cars or motors of any form of construction, and by my improvement I provide means whereby only that portion of the third rail over which a car or motor is passing is energized and in this way the third rail is rendered harmless and no injury can be occasioned by coming in contact therewith.

In the drawing forming part of this specification, I have shown the third rail, with its contact surface directed upwardly so that the contact shoes *g* bear on the top thereof, but this arrangement of said parts is not absolutely necessary and other arrangements thereof may be adapted, and various other changes in and modifications of the construction herein shown and described may be made without departing from the spirit of my invention or sacrificing its advantages. I have also shown and described each of the third rail sections *b*² as provided with two of the armatures *e*⁵, but this arrangement also is not absolutely necessary as one or more of said armatures may be employed in connection with each of the third rail sections.

Having fully described my invention, what I claim as new and desire to secure by Letters Patent, is:—

1. A third rail for electric railways, the same being a hollow rail composed of an upper and a lower part united

together but insulated from each other, armature supports within said rail having separated uprights provided with notches in their upper ends, armatures lying between said uprights and having pins engaging said notches, and an electric connection for said armatures, substantially as described.

2. A hollow third rail for electric railways composed of an upper part, and a lower part, each having downwardly inclined flanges at the sides, the two parts being connected together with an insulating material between said flanges

insulating said parts from each other, substantially as described.

In testimony that I claim the foregoing as my invention I have signed my name in presence of the subscribing witnesses this 15th day of June 1904.

CHARLES KOZESNIK.
